UNITED STATES PATENT OFFICE.

WILLIAM DZIEZYC, OF MIDDLETOWN, NEW JERSEY.

DESIGN FOR A NAIL-SET.

52,310.

Specification for Design.

Patented Aug. 27, 1918.

Application filed November 22, 1917. Serial No. 203,453. Term of patent 7 years.

To all whom it may concern:

Be it known that I, WILLIAM DZIEZYC, a citizen of Russia, residing at Middletown, in the county of Monmouth and State of New Jersey, have invented a new, original, and ornamental Design for a Nail-Set, of which the following is a specification, reference being had to the accompanying drawing, forming part thereof.

Fig. 2 is a side elevation thereof.

I claim:

The ornamental design for a nail set, as shown.

WILLIAM DZIEZYC.

Witness:

A. ALVIN WHITING.
